WASH PIPE

Lyle C. Tilbury, Houston, Tex.

Application June 3, 1932, Serial No. 615,163

3 Claims. (Cl. 166—20)

This invention relates to a wash pipe and has particular relation to a novel type of wash pipe to be used in the process of washing a well screen preparatory to bringing in a well.

5 An object of the invention is to provide a novel type of wash pipe, whereby a washing fluid may be conducted down through a well screen and out at the lower end of the screen and up through the bore outside of the screen whereby the 10 screen may be thoroughly washed and cleansed, said wash pipe being equipped with inlet valve means whereby the oil or other fluid produced from the well may be permitted to flow into the wash pipe, and thence up to the surface 15 without the necessity of lifting the wash pipe off of its seat at the lower end of the screen.

In the production of oil, a casing is usually set in the well above the producing strata and a screen is set in the well beneath the casing 20 opposite said strata and the screen is then

washed to thoroughly cleanse it of all clogging material. For the purpose of washing the screen a wash pipe is usually let down through the screen and its lower end is seated in a wash pipe 25 seat at the lower end of the screen and through this wash pipe the washing fluid is conducted down through the screen and passes out at the lower end of the screen and thence up about the outer side of the screen to wash the same.

30 A packer is then set between the upper end of the screen and the lower end of the casing to form a fluid tight joint. When the well and screen are thoroughly washed it often happens that the well is ready to come in, that is, that 35 the well is ready to start flowing from the producing strata and in such case in order to permit the oil to flow out it is necessary to elevate the wash pipe off of its seat so that the oil can enter the wash pipe and flow on out of the well, 40 if the ordinary wash pipe is used.

It is the prime object of this invention to provide a novel type of wash pipe which need not be lifted off of its seat in case the well starts to flow, and which is equipped with inlet valve 45 means which will prevent the escape of the washing fluid but which will permit the oil to flow inwardly through the screen and into the wash pipe without the necessity of elevating the wash pipe off of its seat.

50 With the above and other objects in view the invention has particular relation to certain novel features of construction, arrangement of parts and use, an example of which is given in this specification and illustrated in the accompanying drawing, wherein:

Figures 1, 2 and 3, show elevational views partly in section of the upper, intermediate and lower sections, respectively of the wash pipe, shown in assembled relation with the packer and setting tool, and screen as set in a well bore, and

Figure 4 shows a cross sectional view taken on the line 4—4 of Figure 3.

Referring now more particularly to the drawing wherein like numerals of reference designate similar parts in each of the figures, the numeral 1 designates a casing as set in a well bore and beneath this casing is a well screen 2 of any selected design. Attached to the lower end of the screen there is the set shoe 3 having 70 the outlet opening 4 at its lower end and provided with the conventional downwardly opening back pressure valve 5 and the tubular seal valve 6 whose upper end has the wash pipe seat 7.

Attached to the upper end of the screen there is a tubular packer support 8 around which there is an expandable packer 9 whose lower end is secured to said support and whose upper end is secured to the tubular setting nipple 10. Any selected type of packer and setting tool may be employed, such as are now in common use. Various types of packers and packer setting tools are commonly employed for forming a fluid tight seal between the upper end of the screen and the lower end of the casing and these various types are well known to those familiar with the art of completing oil wells and producing oil and for that reason a specific description of these parts will not be given as they form no part of the present invention. As a well is drilled the casing 1 is set usually, above the oil bearing strata and the well is drilled on down beneath the casing into the producing strata. The screen 2 is set beneath the casing opposite the oil bearing strata.

In order to set the screen it is attached to the lower end of a tubular string of pipe as 11 with the packer and setting tool incorporated into the setting string above the screen. The screen is then let down into the well until it rests on the bottom of the bore. When the screen, packer and setting tool are assembled with the setting string 11 a wash pipe 12 is assembled therewith and is let down with the screen. The lower end of this wash pipe is seated in the wash pipe seat 7 and when the screen is landed on the bottom of the bore it is desirable that the screen be washed to free it from clogging material and in order to accomplish this a clean washing fluid is forced down through the setting 110

string 11 and passes on down through the wash pipe 12 and through the seal valve 6 past the back pressure valve 5 and out through the opening 4 and thence back up around the screen 2 to wash the same, and when the screen is washed the packer 9 is then expanded, or set, in the casing and the well is then ready to be brought in. It often happens that when the well is washed the oil immediately starts flowing, but 10 with the present type of wash pipe now commonly used, the oil entering through the screen is blocked by said wash pipe until the wash pipe is elevated so as to carry its lower end up out of the seat 7 and the oil can then flow into the 15 wash pipe and on up through the string 11 to the ground surface.

The improved type of wash pipe herein described is provided with one or more inlet openings 13 and these openings are normally closed 20 by the inwardly opening valves 14.

As shown the openings 13 are elongated longitudinally and the valves 14 are flexible and have their lower ends anchored to the wash pipe and the upper ends free. These valves are secured 25 to the inner side of the wash pipe so as to open inwardly.

As the washing fluid is forced downwardly through the wash pipe to wash the screen the valves 14 will be held tightly closed to prevent 30 the escape of the washing fluid through the openings 13 but after the screen has been washed and the packer set the oil produced by the well may flow inwardly through the screen and through the openings 13 into the wash pipe and 35 thence on up out of the well.

Any number of openings 13 and valves 14 may be employed and may be spaced along the wash

pipe as desired to give the wash pipe the required inflow capacity.

After the well has ceased voluntarily flowing or at any time desired, the wash pipe may be removed from the well in the usual way along 80 with the packer setting tool and string 11 and the well may be equipped with the usual pump for pumping the same or deepened if desired.

The drawing and description disclose what is now considered to be a preferred form of the 85 invention, by way of illustration only, while the broad principle of the invention will be defined by the appended claims.

What I claim is:

1. The combination with a well screen having 90 a wash pipe seat, a wash pipe in the screen whose lower end is received by said seat, said wash pipe having an inlet opening above said seat and an inwardly opening valve controlling said opening.

2. The combination with a well screen having 95 a wash pipe seat adjacent the lower end thereof, of a wash pipe in the screen whose lower end is supported by said seat, said wash pipe having a plurality of inlets through the wall thereof and inwardly opening valves controlling said inlet. 100

3. In apparatus for producing fluid from a well and embodying a screen having a seat adjacent the lower end thereof and means for forming a seal between the upper end of the screen and the walls of the well; a wash pipe extending from 105 above the seal down through the screen and whose lower end rests on said seat, said wash pipe having an inlet opening through the wall thereof and a valve controlling said opening and permitting the flow of fluid inwardly, only, through 110 said opening.
